(57) **CLAIM**

The ornamental design for a drill with measurement system insert, as shown and described.

DESCRIPTION

FIG. 1 is a perspective view of a drill with measurement system insert;

FIG. 2 is a left side view of the drill with measurement system insert of FIG. 1;

FIG. 3 is a right side view of the drill with measurement system insert of FIG. 1;

FIG. 4 is a front view of the drill with measurement system insert of FIG. 1;

FIG. 5 is a rear view of the drill with measurement system insert of FIG. 1;

FIG. 6 is a top view of the drill with measurement system insert of FIG. 1; and,

FIG. 7 is a bottom view of the drill with measurement system insert of FIG. 1.

The broken lines in the drawing indicate environmental structure and form no part of the design to be patented.

1 Claim, 5 Drawing Sheets
